GRID PANEL UNIT FOR RADIANT HEAT
AND LIKE INSTALLATIONS

John Graham, Jr., Falls Church, Va.

Application January 7, 1947, Serial No. 720,524

2 Claims. (Cl. 257—255)

1

The present invention relates to panel units for radiant heat and like installations and aims generally to provide an improved prefabricated panel coil unit for such installations.

As is well known, the principles of radiant heating have been well established and involve the transmission through space of heat-carrying rays which generally have a minor effect upon the temperature of the space, but when intercepted by a solid object, act to heat the exposed surface of that object. If the intercepting surface is the human body exposed to cold atmospheric surroundings, the intercepted heat rays tend to offset the body's surface heat loss to the surrounding air, thus producing a sensation of warmth.

Radiant heat installations usually involve circulating a heating fluid, for example water, within conduits such as pipes or tubes embedded within a floor, wall or ceiling of a room so as to heat the surrounding material by conduction, which material dissipates its heat by radiation. In such installations the heat transfer is not solely by radiation but is partly by convection, the relative proportions of heat transfer by convection and by radiant transfer varying somewhat by the location of the heating panel unit. For example, it has been stated that where the heating panel unit is embedded in a floor of a room, the heat transfer is 45 per cent by convection and 55 per cent by radiant transfer; for side wall installed panel units the heat transfer is 40 per cent by convection and 60 per cent by radiant transfer, and for ceiling installed panel units the heat transfer is 33 per cent by convection and 67 per cent by radiant transfer.

Accordingly, in the interests of economy it is desirable to employ ceiling installed panel units for radiant heating systems where such installations are possible.

Conventionally, radiant heating systems installed in ceilings, walls and floors of buildings are operated by circulating a heating fluid, for example water, through thin walled, light weight pipes or tubes in the form of flat coils embedded in the plaster or cementitious material of the wall structures. Such pipes or tubes conveniently are light weight flexible copper or aluminum tubing of approximately $\frac{1}{4}$ ", $\frac{3}{8}$ ", or $\frac{1}{2}$ " soft temper tubes in the form of a flat coil, the straight runs of which are suitably spaced, as for example $4\frac{1}{2}$ ", 6", 9" or 12" on centers according to calculation based on the make-up of heat losses from the interior of structures to the atmospheric exterior. The coils may extend either

partly across or entirely across the room from side wall to side wall and the coils for each space or room are connected to the fluid distributing system by supply and return risers.

5 The installation of ceiling installed radiant heat units heretofore has been expensive and laborious work. The tubing usually has been supplied in standard coils of 40 to 60 feet in length, which is progressively uncoiled and attached to the ceiling plaster lathing by a workman or workmen who must carefully measure and lay out the position of each straight run in accordance with the calculated heating layout for the room, as well as making the return bends 10 in the tubing, taking care not to unduly flatten the flexible tubing. No matter what hand method is devised by the workmen at the job, whether bending and attaching the tubing in place on the ceiling or forming the bends on the floor and lifting sections and attaching them in place, the entire process is so slow and laborious that the labor installation costs on the job are excessive and often prohibitive, and besides, many workmen dislike making such installations because of 15 the arduous labor involved in making overhead installations. Moreover, with such prior methods of installation where the tubing is secured tightly to the lath there is no opportunity to obtain desired spaced relationship between the tubing and the plaster lathing for the purpose of insuring the tubing being wholly embedded in the plaster or cementitious coating, which condition is necessary to the efficiency of radiant heat installations, and further, frequently the sections of 20 tubing forming the coil are not level and thus likely to detrimentally affect the proper installation and operation of the system.

One of the primary objects of the invention is the provision of a prefabricated panel unit for radiant heat and like installations which may be 25 more readily and easily installed and connected by the heating contractor to form a coil after the plaster contractor has installed the desired plaster lathing base.

Another object of the invention is the provision of an improved panel unit that may be readily and economically prefabricated in desired sizes either for shipment to the job or which may be quickly installed on the job with a minimum of effort and at a minimum of expense.

A further object of the invention is the provision of a panel unit for radiant heat and like installations in the form of a grid composed of open ended pipe or tube sections secured to stiffening and nailing members so as to properly

maintain a desired spaced relationship between the tubing and a plaster lathing base and at the same time provide a maximum of nailing openings for secure attachment of the grids to available supports such as joists, studs or the like.

A still further object of the invention is the provision of a grid panel composed of separate sections of tubing held in proper assembled spaced relationship and so constructed that secure nailing or attachment of the sections to the supporting wood, steel or concrete joists or rafters of a building will be insured regardless of variations in spacing of said joists and rafters.

Other aims and objects of the invention will appear to persons skilled in the art from a consideration of the accompanying drawings and annexed specification illustrating and describing a preferred embodiment of the invention.

In the drawings:

Fig. 1 is a plan view of a typical radiant heat panel installation in a ceiling of a room and embodying grid panel units according to an embodiment of the invention;

Fig. 2 is a sectional view thereof as taken on the line 2—2 of Fig. 1;

Fig. 3 is a sectional view similar to Fig. 2 but illustrating the heating grid panel applied to a plaster lathing base of the wall board type;

Fig. 4 is an enlarged sectional view as taken on the line 4—4 of Fig. 1;

Fig. 5 is an enlarged sectional view as taken on the line 5—5 of Fig. 4;

Fig. 6 is a plan view of disassembled grid panel units or sections according to the invention and which may be readily assembled and connected to form a continuous coil; and

Fig. 7 is an enlarged detail sectional view illustrating the manner of attaching the tubing to the stiffening and nailing members.

Referring to the drawings, the invention is illustrated as adaptable for and as applied to a ceiling wall of a building though it will be apparent that it is equally adaptable to side wall and floor installations. Accordingly, as used herein, the term "wall" includes a ceiling structure as well as a side wall or floor structure and includes preferably a monolithic structure embodying cementitious material, for example plaster, secured to a supporting lathing base, which base in turn is secured by nailing or otherwise to supports such as the joists or studs of buildings.

In the drawings, the invention is shown incorporated in a ceiling wall which may include the usual floor joists 1 to which a lathing base has been applied, this work being usually performed by the plastering contractor in advance of the installation of the heating system. The lathing base may be of the metal lath of various types 2, (Fig. 2) or of wood lath or of the wall board type 3 (Fig. 3), such as gypsum lath or fiber insulating lath and the like.

The heating coil or coils (see Fig. 1) are preferably composed of a plurality of straight runs 5 of tubing extending partly across or entirely across from side wall to side wall and spaced sufficiently apart to compensate for the heat loss of the room. It will be understood that these straight runs 5 will be variously spaced, depending upon the calculated heat loss, and may be, for example, 4½", 6", 9" or 12" on centers or on any required spacing. These straight runs 5 are connected at their ends by reverse or U-bends 6 and 7, the terminal ends 8 and 9 of the coil being connected to supply and return risers 10 and 11, respectively, for the supply and return of

the heated fluid from and to the heating plant. The coil is designed to be embedded in and become an integral part of a monolithic ceiling or side wall so as to supply heat to the wall over a substantial area.

The heating coils are conveniently formed of light weight thin walled tubing, for example ¼", ¾" or ½" copper tubing, weighing approximately ½ to ¾ pounds per foot of tubing. Such tubing is exceedingly flexible and is easily bent, this being a desirable feature from the standpoint of weight and cost.

According to the invention, the coil is composed of sections of open ended tubing held together in predetermined spaced relation by rods or stiffening members later to be described. Preferably, as shown in Fig. 6, each coil panel is composed of one or more sections A composed of a plurality of open ended straight tube sections 5, a right hand section B composed of a plurality of U-shaped bends of tubing 6, and a left hand section C composed of a plurality of U-shaped bends of tubing 7. The several pieces of tubing of each section are individually secured to stiffeners or nailing strips 15 which are suitably spaced apart in accordance with the length of each section, and of sufficient number to be attached to each joist or stud 1, there being preferably at least two stiffening bars 15 for the tubing of each section. The ends of the tubes of one of the sections, for example the tubes 6 and 7 of the end sections B and C, may be fitted with couplings 12 adapted to be connected as by soldering or brazing to the open ends of the tubes of the middle sections, though it will be apparent that the couplings may be on opposite ends of the middle section if desired.

As is illustrated in Fig. 6, each of the end sections B and C may include a plurality of U-shaped tubing sections 6 or 7 and a single straight section 6^a and 7^a which may have couplings 12 attached to the opposite ends.

The stiffening or nailing members 15 are preferably of flat metal bars of suitable width and thickness, provided with a longitudinal series of nailing or attaching holes 16. These holes 16 are suitably spaced, as for example on ½ or ¾ inch centers, so as to provide at least one nailing or attaching hole for each supporting stud or joist when the stiffening and nailing members 15 are disposed perpendicularly to the supporting pieces 1. The stiffening and nailing members 15 will be of sufficient thickness to set the position of the sections of tubing 5, 6 or 7, sufficiently away from the plaster lathing base 2 or 3 so as to permit the plaster or cementitious layer 4 above to entirely surround the tubing.

The tubing sections 5, 6 and 7 of the respective sections A, B and C may be attached to the stiffening and nailing strips 15 by suitable fastenings which, in the illustrated embodiment, may comprise a clip or saddle member having a bight portion 20 adapted to underlie the tubing with apertured end flanges 21 for attachment to the stiffening or nailing strips 15. The clips or saddle members may be attached to the stiffening members 15 by suitable means, as for example, a hollow tubular rivet 22 passed through aligned apertures of the flanges 21 and the nailing openings 16 of the members 15, one end of the rivet being upset or otherwise clenched with the inner face of the member 15, as at 23. The use of a tubular type fastening 22 for this purpose is of advantage in that it provides a passage for a nail 17 or like attaching member for

securing the grid panels to a supporting stud or joist 1. Such fastenings embodying a saddle member 20 and tubular rivets 22 are of advantage in that they may be quickly and cheaply applied, and provide an initially loose connection between the tubing 6 and stiffening member 15, permitting ready shifting of the latter along the tubing to a position where it may be aligned with a supporting joist or stud 1, in such cases where the stiffening member is disposed parallel to the joists or studs 1, as shown in Figs. 2 to 5 inclusive. When the grid panel is nailed or attached to the supporting joists or studs 1 by driving the nail 17 through the tubular rivet 22, the saddle member 20 is drawn against the stiffening member 15 securely clamping the tubing in place.

From the above description it will be understood that the sections A, B and C may be prefabricated at the factory in various sizes and lengths to suit the particular requirements, and shipped to the job, there to be readily assembled and connected to provide a continuous coil, as shown in Fig. 1, of desirable width, depending upon the length of the middle straight run section A. The several sections A, B and C may be nailed to the supporting joists or studs 1 under the previously applied plaster lathing base 2 or 3, by nailing through the apertures 16 of the strips 15 and preferably through the tubular rivets 22 of the fastenings 20. To facilitate this nailing, the strips 15 with the fastenings 20 are readily shiftable along the length of the tubing 5, 6 and 7 to be aligned with the studs or joists 1, thus avoiding the necessity of installing cats or like transverse nailing strips in the supporting framework.

After the sections A, B and C have been secured in place, as above described, the adjoining open ends of the tubes of the adjacent sections may be readily connected by soldering or brazing the plain ends of one into the couplings 12 or fitted ends of the other. The extreme flexibility of the thin walled light weight tubing permits the ready bending of the tube ends into the adjoining couplings 12, following which a workman may quickly solder the two together. The terminal ends of the coils are then ready for connection to the supply and return risers 10 and 11. In shorter lengths the middle section A may be omitted, in which case the sections B and C may be joined together to form a grid panel.

As above stated, the tubes are spaced from the plaster lathing 2 or 3 a predetermined distance, as determined by the thickness of the stiffening and nailing strips 15, which affords space for the proper application of the plaster coat 4 around the tubes so as to completely embed the tubes in the plaster coats and thus form a monolithic structure.

In addition to the advantage of insuring accurate installation of the tubing both as to straightness and alignment of the tube sections as well as even and proper spacing thereof from the lathing base, necessary to the most efficient functioning of radiant heating systems, the invention has the advantage of very materially reducing the labor cost of installation. Relatively unskilled workmen may install a radiant heat grid panel embodying this invention in approximately one quarter to one half the time formerly required of skilled workmen employing the prevailing

methods. In addition, this invention relieves the workmen of many arduous duties of measuring and bending the tubing in overhead installations.

It will be apparent to persons skilled in the art that the sections A, B and C may be prefabricated in sizes suitable for packaging and convenient shipment, and at the same time permitting them to be readily connected together to form a grid panel of any desired length and width.

The term "radiant heat and like installations," as used herein, is intended to apply to cooling systems as well, wherein a cooling fluid, for example cold water, may be circulated through the coils of tubing. As will be apparent, this will have a desirable cooling effect upon a space, and would be desirable in those localities where atmosphere humidity is sufficiently low so as not to cause condensation on surfaces adjacent the cooling medium.

Although I have illustrated and described my invention with particular reference to one preferred embodiment thereof, I do not intend that it be limited to the details of construction shown and described, as the scope of the invention is best defined in the appended claims.

I claim:

1. A grid panel for radiant heat and like installations comprising a length of flexible tubing providing a plurality of parallel runs, a plurality of relatively narrow stiffening members disposed transversely of said runs and provided with a plurality of apertures, saddle-shaped fastener means disposed on one of the faces of said stiffening members and loosely embracing said runs of tubing, said saddle-shaped fastener means being provided with apertured ends, and tubular nail-receiving attaching means passed through the apertures of said saddle-shaped fastener and stiffening members for maintaining said parts in assembled relation.

2. A grid panel for radiant heat and like installations comprising a length of flexible tubing providing a plurality of parallel runs, a plurality of relatively narrow stiffening members disposed transversely of said runs and provided with a plurality of apertures, saddle-shaped fastener means disposed on one of the faces of said stiffening members and loosely embracing said runs of tubing, said saddle-shaped fastener means being provided with apertured ends, and tubular rivets passed through the apertures of said saddle-shaped fasteners and stiffening members, said tubular rivets providing an axial passage for a nailing element to secure said panel to a supporting structure.
